Primary Examiner — George D. Kirschbaum*Assistant Examiner* — Maria J Edwards**CLAIM**

The ornamental design for an anti-impaction glove, as shown and described.

DESCRIPTION

FIG. 1 is a front plan view of an anti-impaction glove, showing the new design;

FIG. 2 is a back plan view thereof;

FIG. 3 is a right plan view thereof;

FIG. 4 is a left plan view thereof;

FIG. 5 is a top plan view thereof;

FIG. 6 is a bottom plan view thereof; and,

FIG. 7 is a perspective view thereof.

The broken lines in the drawings depict portions of the anti-impaction glove and form no part of the claimed design.
